UNITED STATES PATENT OFFICE.

GEORGE NOPOLION THERRIEN, OF KEENE, NEW HAMPSHIRE.

SPIKE-DRIVING MACHINE.

1,412,222.

Specification of Letters Patent. Patented Apr. 11, 1922.

Application filed May 31, 1921. Serial No. 473,672.

To all whom it may concern:

Be it known that I, GEORGE NOPOLION THERRIEN, a citizen of the United States, residing at Keene, in the county of Cheshire 5 and State of New Hampshire; have invented new and useful Improvements in Spike-Driving Machines, of which the following is a specification.

My present invention has reference to a 10 machine for spiking rails to ties.

The improvement is in the nature of a respiking machine, that is a machine designed for driving home loose spikes, and the primary object of the invention is to produce 15 a machine for this purpose which will be automatic in action.

A further object is to produce a machine for driving home loose spikes in the supporting ties for railway rails that is mounted on 20 a truck which travels on the rails and that is provided with a feeler member for contacting the spikes on one of the sides of the rails which actuates driving means in the nature of a hammer that forcibly contacts with the 25 spikes on each side of the rails for effectively driving such spikes home.

A still further object is to produce a respiking device in which a feeler member is disposed in advance of normally elevated 30 spring influenced hammers and which after contacting with a spike on one of the sides of the rails will actuate means for releasing the hammer to cause the same to forcibly contact and drive home the spikes on both 35 sides of the rails, means being provided for holding the feeler member out of the path of engagement with the hammer previously to and immediately after the engagement of the hammer with the spikes, means being 40 provided for returning the hammer to its initial position and thereafter returning the feeler to active position whereby the same will be brought into the path of contact with the next spike on the succeeding tie, and 45 again cause the operation of the hammer, all of such means being automatic in action.

The foregoing, and many other objects which will present themselves as the nature of the invention is better understood, may be 50 accomplished by a construction, combination and operative association of elements such

as is disclosed by the drawings which accompany and which form part of this application. The nature of the invention is such as to render the same susceptible to various 55 changes in size, form, proportion and other details of construction, all of which, however, falling within the scope of what is claimed.

In the drawings:—

Figure 1 is a side elevation of the improvement mounted on the rails of a track.

Figure 2 is a top plan view thereof.

Figure 3 is a sectional view on the line 3—3 of Figure 2.

Figure 4 is a sectional view on the line 4—4 of Figure 2.

Figure 5 is a sectional view on the line 5—5 of Figure 1.

Figure 6 is a sectional view on the line 6—6 of Figure 1.

Figure 7 is a sectional view on the line 7—7 of Figure 1 and showing the manner in which the spike contacting or feeler member is held inactive until after the hammer has 75 been returned to its initial elevated position.

Figure 8 is a sectional view on the line 8—8 of Figure 2.

Figure 9 is a fragmentary elevation, with the shaft 37 in section, and showing the 80 ratchet wheel thereon engaged by the pawl which is pivotally supported on one of the members of the frame.

Figure 10 is a plan view showing the feeler member about to engage a spike, the 85 shaft for the feeler member being in section.

Figure 11 is a sectional view on the line 11—11 of Figure 7.

In the drawings, the rails of a railway track are indicated by the numeral 1, the 90 supporting ties for the rails by the numeral 2, and the spikes which secure the rails to the ties by the numeral 3.

In the present method, as far as I am aware, railroad concerns employ track walkers for tightening loose bolts on rail joints and for driving home loose spikes. Because of the vibration to which the rails are subjected and also because of splits or crevices in the ties, the spikes are comparatively 100 easily loosened from engagement with the rails, and because of this many accidents

have occurred. It will be apparent, as the description progresses that with my improvement every spike, whether loosened or not, will be contacted by the hammer of the device, the loosened spikes driven home, and the spikes not materially loosened more effectively forced into engagement with the rails.

As disclosed by the drawings, I make use 10 of a truck 4 which may be of any desired size and proportion, and may be and preferably is, of the ordinary construction in common use on rails. The truck may be hand propelled or may be of the type that 15 is manually moved along the track. In the showing of the drawings I have illustrated the truck provided at one end with a frame extension, the said frame projecting over one of the rails 1. It will be apparent, and 20 it is to be understood that the truck may be constructed to include this frame, and also that the mechanism supported on the frame over one of the rails may be duplicated, and arranged over the other rail.

25 The frame has journaled at its forward end the axle of a wheel 6 which travels on one of the rails 1 and which supports the forward end of the frame. The frame includes longitudinally spaced members 7 and 30 transverse members 8 connecting the said longitudinal members. To the rear of the wheel 6 I bolt to the inner confronting faces of the longitudinal members 7 a substantially U-shaped housing 9. The housing is 35 wholly constructed of metal, and has its parallel side members hollow for the major length thereof to provide substantially rectangular pockets 10. The pockets are open at the top of the housing, and the inner or 40 confronting walls of the side members 11 that are provided with the pockets have central openings 12 therethrough, the said openings being of a length equalling that of the pockets. The side members 11, at their upper 45 corners have outstanding lips 13 to receive therebeneath the inturned lips 14 formed on the flanged ends 15 of cover plates 16. The lower or connecting wall 17 for the sides of the housing 9 is provided 50 with a pair of spaced vertically disposed substantially rectangular openings 19 and a centrally arranged transverse round opening 20 between the openings 19. Depending from the under face of the horizontal wall 55 of the casting which I have referred to as the housing is a lug 21 of a width greater than that of the head of the rail 1 which it overlies. The lug has its lower end bifurcated, and the spaced arms 22, thus provided, are disposed to the opposite sides of 60 the head of the rail 1, but are out of contact with the said head of the rail. Journaled in suitable bearing openings in the arms 22 is the shaft 23 for a roller 24, the said roller 65 riding on the head of the rail 1. If desired,

the shaft 23 may be influenced by suitable spring means for holding the roller against the tread surface of the rail.

Two hammer members are employed, each of a similar construction. The hammer members are formed of suitable metal and are each substantially rectangular in cross section. Each hammer member is indicated by the numeral 25 and is received through the respective openings 19 in the lower wall 70 of the casting providing the housing 9. The portion of each of the hammer members 25 projecting above the lower wall of the housing is formed with a substantially rectangular extension or widened portion 26 at the 75 diagonally opposed inner corners or faces of the respective hammer members 25. These rectangular enlargements are disposed side to side and may be in contacting engagement with each other. As a matter of fact, 80 the hammer may be constructed from a single element to provide the upper widened or body portion on the sides or legs that pass through the openings 19. Each of the hammer members, at the portion thereof disposed above the lower wall of the housing 9 has an angle finger 27 that is received through the respective openings 12 on the sides 11 of the housing 9. The upper face 85 of each of the fingers is flat and has resting thereon a plate 28. If desired the plates may be secured to the fingers. On the plates 28 rest strong helical springs 29. The upper ends of these springs bear against plates 30. Each of the cover plates 16 has its outer 90 face centrally enlarged by a boss providing a threaded opening and in each of these openings there is the threaded shank 31 of a headed bolt member 32. By adjusting the bolts, the tension of the springs will be regulated. The springs, together with the weight of the hammers are at all times sufficient to forcibly move the hammers downwardly into contacting engagement with the spikes on the opposite sides of the rail 1, 110 and the width of the hammers equals or is slightly in excess of the width of the ties 2 in which the spikes 3 are driven.

On the upper face of the wall 17 of the casting 9 there is a yieldable buffer 33 115 against which the lower edges of the widened upper portions of the hammer members contact when the same are influenced by their springs to spike engaging position. Each of the hammer members has its lower end provided with a transverse dove tail slot 34 that receives therein a dove tail lug 35 on a head member 36 of hardened metal. The heads 36 contact with the heads of the spikes when the hammer is brought to driving 120 position.

Passing through the opening 20 in the portion 17 of the casting 9 is a shaft 37. On this shaft, at the opposite sides of the hammer members are cam wheels 38 and 39 130

respectively. On the sides of the widened upper portions of the hammer members are stub shafts or lugs 40. On each of the stub shafts 40 there is a roller 41. The stub shafts 5 are directed toward the respective cam wheels 38 and 39, so that the rollers 41 thereof are engaged by the cam surfaces of the said wheels when the shaft 37 is moved to one position (in a manner which will presently be described), so that the hammer members 10 are normally retained elevated against the tension of their springs.

The shaft 37 finds bearings in suitable boxings provided in openings in the transverse members 8 of the frame 5, and the said shaft is held against turning in one direction through the medium of a ratchet wheel 42 that is secured thereon and that is engaged by a pawl 43 that is pivoted to one of the 20 transverse members 8 of the frame. The purpose of the pawl and ratchet is to hold the shaft from turning by the pressure exerted on the cam wheels 38 and 39 by the weighted hammer members and the springs 25 that influence the said hammers.

On either the frame or the truck there is a motor 44. If desired this motor may provide means for propelling the truck. The shaft of the motor has secured thereon a 30 gear wheel 45 which is in mesh with a pinion 46 that is loose on the shaft 37. The pinion 46 is held against longitudinal movement on the shaft 37 by means on the opposite side thereof indicated by the numeral 47. 35 The pinion on its outer face, or the face thereof confronting the hammer and casting 9 is provided with or has secured thereon a toothed clutch wheel 48. The shaft 37 has its sides outward of the clutch wheel 40 grooved to provide seats for keys or feathers 49 that are received in grooves 50 in the bore of a clutch wheel 51. The clutch wheel 51 is influenced by springs 52 carried by a collar member 53 secured on the shaft 37 45 by means 54, in the direction of the clutch wheel 48, and when in such engagement, the shaft 37 will be turned by the motor. The clutch element or wheel 51 is normally sustained out of engagement with the clutch 50 wheel 48 by means which will presently be described.

On the inner face of the frame 5 there is a depending bracket 55, whose lower vertical portion is in the nature of a sleeve 55 that provides a bearing for a vertically disposed shaft 56. The shaft 56 carries at its upper end a beveled pinion 57, while adjustably supported on the portion thereof depending below the bearing sleeve, by 60 means 58 is an arm 59. The outer end of the arm is preferably widened, rounded and depressed, and the upper face of the said rounded portion is serrated. This portion 60 of the arm 59 is in contacting engagement 65 with a similar rounded or head portion 61

provided on one end of the feeler member 62. Between the head portions 60 and 61 of the arm 59 and the feeler member 62 there is passed a bolt 63 that is engaged by a winged nut 64. The arm 59 is both vertically and circumferentially adjustably connected to the shaft, and the feeler member is pivotally connected to the arm. Thus it will be noted that the feeler may be arranged at desired elevations with respect to the horizontal base flanges of the rails over which the feeler travels, and also the same may be disposed at any desired inclination with respect to the arm and to the shaft on which the arm is supported. The feeler member 80 is in the nature of a bracket, having the portion thereof formed with the head 61 provided with a downward angle extension 65, and on this extension is an outwardly extended portion parallel with but oppositely 85 extended to the portion of the feeler carrying the head. The portion 65 is in the nature of a finger, and will hereinafter be referred to as such.

Journaled in bearings 66 secured to the 90 inner side of the frame 5 is a horizontally disposed shaft 67. This shaft is held against longitudinal movement by means 68 that are disposed opposite the bearings 66. The shaft 67 carries a beveled toothed pinion 69 that is in mesh with the pinion 57. On the opposite end of the shaft 67 there is secured a cam striker member 70. Pivotally mounted, as at 71 between the arms of the yoke 72 that is secured, as at 73, to the inner 95 side of the frame 5, is an arm 74. This arm is of a peculiar construction, having a straight outer portion on which the striker member 70 rests, an angle portion that is pivotally connected to the yoke, an extension, parallel to its outer portion formed on the inner edge of the central angle portion, the last mentioned portion having its end provided with an upstanding or angle portion 75. The angle end 75 may be slotted or provided with a pocket 76, and in the side walls thus provided there is pivoted, as at 77, one arm of a substantially U-shaped member, while the second parallel arm of the said U-shaped member has an angle 100 extension 78 that passes through an opening in the opposite side wall. The end of the extension 78 has a threaded opening in which is screwed a bolt 79. The bolt is 105 adjustable to engage with the dog supporting yoke 72, and when the substantially U-shaped abutment member is swung by the arm to one position, a spring 80 normally sustains the U-shaped contact member in a horizontal position with respect to its 110 pocket or housing.

On the sliding clutch wheel or member 48 there is integrally formed a lug 81. A dog supporting yoke 82 is supported on the frame 5, the dog which is pivoted therein 115

is indicated by the numeral 83. The dog has its inner end provided on one of its corners with a curved lip extension 84 that underlies the clutch member 51 and that 5 contacts with the lug 81 thereon for holding the clutch member 51 out of engagement with the fixed clutch member 48. The opposite or outer end of the dog is weighted, and is provided on the corner thereof opposite 10 that formed with the lip, with a reduced extension 85. In the space provided between the end of the dog and the said extension 85 the angle end 78 of the arm 74 is received, the U-shaped spring influenced contact member carried by the said arm underlying the extension 85. In reality, the extension provides the tail of the dog.

At the front of the frame, forward of the hammers there are depending shafts 86 20 that carry at their lower ends wire brushes 87. The brushes are flexible, and contacting with the upper surface of the ties remove stones, gravel or other substances therefrom. The shaft 37, when in inactive 25 positions, sustains the cams 38 and 39 in a position whereby the hammers are retained at their highest elevation. The feeler member will contact with the head of a spike on one side of the rail, and by virtue of such contact 30 the said member will be turned to revolve both the vertical shaft 57 and the horizontal shaft 67. The turning of the shaft 67 will cause the striker member 70 to swing the arm 74 on its pivot, bringing 35 the U-shaped striker member against the tail of the dog, swinging the dog to bring its lip out of engagement with the lug 81 on the slidable clutch 51, permitting the springs 52 to move the slidable clutch member in engagement with the fixed clutch member 48, 40 thus turning the shaft. By reason of the U-shaped striker on the arm 74 and its pivotal connection with the said arm the shaft 37 will be permitted one complete revolution to 45 allow the hammer members to be influenced by their springs and by their weight to spike contacting engagement and to be elevated from such engagement to their initial position. On such turning of the shaft the lip 50 84 of the dog 83 will again engage with the lug 81 on the slidable clutch member 51, retracting the said member 51 away from engagement with the fixed clutch member 48, the tail of the dog engaging with the U-shaped contact member of the arm 74 swings 55 the arm to its initial position which influences the cam or striker member 70 on the horizontal shaft 67 to turn the said shaft in a reverse direction which, by the intermeshing 60 of the gear thereon with the gear on the vertical shaft will turn the vertical shaft to bring the feeler member to its initial position whereby the said feeler member will contact with the head of the spike on the 65 next tie over which the device travels. It

will thus be seen that the apparatus is automatic in action. The heads of the hammers, as previously stated, are of a length whereby the spikes on both sides of the rails will be positively contacted with. The construction is simple and may be, as stated, attached to any ordinary railway hand car or truck.

Having described the invention, I claim:—

1. In a machine for driving home loose 75 spikes in ties, hammer members designed to forcibly contact with the spikes, means normally holding said hammers from such contact, means to contact a spike to be driven, and means actuated by said last mentioned 80 means when the latter is influenced by spike engagement for releasing the hammer holding means.

2. In a means for driving loose spikes home, hammer members designed to forcibly 85 contact the spikes, means normally holding said hammers from such contact, means to contact a spike to be driven home, means actuated by said last mentioned means when the latter is influenced by spike engagement 90 for releasing the hammer holding means, and means for sustaining the spike contact means in one position when the hammer is actuated.

3. A rail spiking machine for forcing loose 95 spikes into ties, comprising a body traveling over the rail, a hammer member on the body disposed over the spike, means influencing the hammer to spike engagement, means holding the hammer from such engagement, 100 and means actuating both of said mentioned means at predetermined intervals.

4. A rail spiking machine for forcing loose spikes into ties, comprising a body traveling over the rail, a weighted hammer, 105 spring means influencing the hammer to spike contacting position, means holding the hammer against the influence of the spring means, means for contacting a spike to be driven and to be influenced by such contact, 110 and means operated by said last mentioned means for releasing the hammer holding means and for permitting such means to again engage and elevate the hammer after the latter has contacted with the spike.

5. A rail spiking machine for forcing home loose spikes in ties, comprising a body movable over the rail, a weighted spring influenced hammer designed for contacting the spike, means engaging the hammer for raising the same from spike contacting position against the influence of its spring means, revolute means associated with said last mentioned means, means holding said revolute means inactive, and means in the path of engagement with the spike designed to be influenced by such engagement, and means operated by said last mentioned means when so influenced for permitting the operation of the revolute means.

6. A rail spiking machine for driving home loose spikes in ties, comprising a body traveling over the rail, weighted spring influenced hammers disposed to the opposite sides of the rail and in the path of contact with the spikes on each side of the rail, revoluble means, means thereon engaging the hammers for raising the hammers out of spike contacting position and for permitting the springs to influence the hammers to such position, revoluble means connected with said last mentioned means, means normally holding said revoluble means inactive, means limiting the turning of said revoluble means when the same is active, means in the path of contact with a spike to be driven and influenced by such contact, means operated by said last mentioned means when so influenced permitting the actuation of the revoluble means.

7. A rail spiking machine for forcing home loose spikes in ties, comprising a wheeled body for travel over the rail, vertically movable spring influenced hammer members supported on the body, disposed to the opposite sides of the rail and designed to contact the spikes, cam members engaging the hammers, means for revolving the cams whereby the latter are brought to one position to hold the hammers elevated and when brought to another position to permit of the springs influencing the hammers to spike contacting position, means limiting the turning of the revoluble means, means preventing the turning of said revoluble means except in one direction, means rendering the revoluble means inactive when the cams are positioned to hold the hammers elevated, means in the path of contact with a spike to be driven and influenced by such contact, and means operated by said last mentioned means when so influenced for releasing the holding means of the revoluble means.

8. In a rail spiking machine for driving home loose spikes in ties, a wheeled body arranged for travel on the rail, vertically movable weighted spring influenced hammers supported on the body and arranged to the opposite sides of the rail for contacting the spikes on both sides of the rail, cam means for engaging the hammer members to hold the same from spike contacting position or for permitting the spring means to influence the hammers to spike contacting position, a shaft for the cams, means for revolving the shaft, means holding the shaft against turning in one direction, means limiting the turning of the shaft, means holding the shaft from turning when the shaft has completed one revolution and has positioned the cams to hold the hammers elevated, means in the path of contact with a spike to be driven and influenced by such contact, means actuated by said last mentioned means for releasing the shaft hold-

ing means to permit a complete revolution of the shaft whereby the hammers will be influenced by said spring means to spike contacting position and engaged by the cam means and raised from such position.

9. In a machine for driving home loose spikes in ties, hammer members designed to forcibly contact the spikes, means normally holding the hammers from such contact, a feeler member in the path of contact with a spike to be driven and influenced by such contact, and means actuated by the feeler member when so influenced for releasing the hammer holding means.

10. In a machine for driving loose spikes into ties, hammer members designed to forcibly contact the spikes, means normally holding the hammers from such contact, a feeler member in the path of contact with a spike to be driven and influenced by such contact, means for adjusting said feeler member both vertically and laterally, and means actuated by the feeler member for releasing the hammer holding means.

11. A rail spiking machine for driving loose spikes in ties, comprising a body movable over the tie, a weighted spring influenced hammer supported on the body, for contacting the spike, cam means engaging the hammer for holding the same elevated and for permitting the spring means influencing the same, a shaft for said cam means, means to revolve the shaft, means holding the shaft against turning except in one direction, means preventing the turning of the shaft when the cam means is actuated to hold the hammer elevated, a vertically disposed shaft journaled on the body, a vertically adjustable element thereon, a feeler member pivotally secured to said element and in the path of contact with the spike to be driven and designed to turn the vertical shaft by such contact, means actuated by the turning of the vertical shaft for releasing the holding means of the first mentioned shaft, means again holding the said last mentioned shaft from turning when the same has completed one revolution to permit of the hammer contacting with the spike and for again raising the hammer by the cam means, means sustaining the feeler member out of spike contacting position when the hammer is actuated, and means returning the said feeler member to operative position when the hammer is elevated and the first mentioned shaft held inactive.

12. In a machine for driving home loose spikes in the tie supporting rails, a reciprocating hammer, means for reciprocating the hammer at determined intervals only and when the said hammer has been brought over the spikes to be driven.

13. In a machine for driving loose spikes in the ties which support rails, a reciprocating hammer, means for reciprocating the

hammer at determined intervals when the hammer has been brought over the spikes to be driven, and means for actuating said reciprocatory means in the path of contact 5 with a spike to be driven.

14. In a machine for driving home loose spikes in the ties that support railway rails,

a reciprocatory hammer, means for operating the same, and means in advance of said hammer and in contacting engagement with 10 a spike to be driven for actuating the reciprocatory means for the hammer.

In testimony whereof I affix my signature.

GEORGE NOPOLION THERRIEN.
